US0D1081261S

(12) **United States Design Patent** (10) **Patent No.:** **US D1,081,261 S**
(45) **Date of Patent:** **** Jul. 1, 2025**

(54) **BOTTLE**

(71) Applicant: **EVERICH AND TOMIC
HOUSEWARES CO., LTD.,**
HangZhou (CN)

(72) Inventor: **Huajun Yao**, HangZhou (CN)

(73) Assignee: **EVERICH AND TOMIC
HOUSEWARES CO., LTD.,**
HangZhou (CN)

(**) Term: **15 Years**

(21) Appl. No.: **29/923,059**

(22) Filed: **Dec. 27, 2023**

(30) **Foreign Application Priority Data**

Jun. 27, 2023 (CN) 202330397426.5

(51) **LOC (15) Cl.** **07-01**

(52) **U.S. Cl.**

(57) **CLAIM**

The ornamental design for a bottle as shown and described.

DESCRIPTION

FIG. 1 is a front perspective view of a bottle showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a portion of the perspective view of FIG. 1 enlarged for magnification purposes.

The broken lines depict portions of the bottle that form no part of the claimed design.

1 Claim, 9 Drawing Sheets
